UNITED STATES PATENT OFFICE.

KITTEL ANUNSEN, OF WINCHESTER, WISCONSIN.

HARVESTER-REEL.

SPECIFICATION forming part of Letters Patent No. 276,148, dated April 24, 1883.

Application filed September 28, 1882. (No model.)

To all whom it may concern:

Be it known that I, KITTEL ANUNSEN, a citizen of the United States of America, residing at Winchester, in the county of Winnebago and State of Wisconsin, have invented certain new and useful Improvements in Harvesters, of which the following is a specification, reference being had therein to the accompanying drawings.

10 This invention has relation to improvements in harvester-reels; and it consists in the novel construction and arrangement of various parts of the reel, whereby said reel may be shifted to different positions, all of which will be hereinafter more fully explained.

15 The annexed drawings, to which reference is made, fully illustrate my invention, in which—

Figure 1 represents a perspective view of my harvester. Fig. 2 represents a cross-sectional view of the same.

20 The letters A A' designate the two uprights in rear of the machine, which are connected at their lower ends by the frame a, on which the same is supported, and at the top said uprights are connected and braced by means of a horizontal bar, a', that is provided on each end with a segment, a², that meshes with segments a³ a³ at the rear ends of the reel-bars a⁴ a⁴. Said bars are connected to one another at their rear 25 ends by a horizontal bar, a⁵, which carries at one end an upwardly-bent arm, a⁶, and at the other end a hand-lever, a⁷.

25 B indicates a horizontal bar, the rear end of which is secured to the inner upright, A', and the opposite end is suitably attached to the main frame of the machine. Said bar has arising therefrom and near the center thereof a standard, b, which is forked at its upper end, in which is pivoted one of the reel-bars a⁴, and 30 near the front end said bar is provided with a slotted standard, b', in which the forward end of one of the reel-bars works and is guided in its up and downward movement thereby. The outer reel-bar a⁴ is pivoted to the forked upper 35 end of an inclined standard or bar, b², secured to the frame of the machine, as shown at b³ in the drawings. The reel-bars a⁴ a⁴ are each provided with guide-loops b⁴ b⁴ b⁴ b⁴, through which slide two bars, b⁵ b⁵, one on each of the reel-bars, 40 as shown, and the outer ends of these sliding bars are provided with bearings b⁶ b⁶, in which

is placed the ends of the reel-shaft b⁷, which has on its inner end a pulley, c, that connects by an endless band or chain, c', with a pulley, c², on the operating-shaft, that receives its motion from the mechanism of the machine. The sliding bars b⁵ b⁵ are provided at their rear ends with eyes c³ c³, in which one end of the connecting-links c⁴ c⁴ are pivoted, while the opposite end of said links are connected to the bent arm a⁶ and the hand-lever a⁷ on the shaft or bar a⁵.

55 To the side of the standard b is pivoted the rear end, c⁵, of a bar, c⁶, which is provided in its forked free end c⁷ with a grooved pulley, c⁸, that bears against or upon the belt or chain aforesaid, thereby keeping the latter taut.

Having given a description of the different parts of which my invention relates, I will now explain the operation of the same in shifting 70 the reel to different positions.

When it is desired to raise or lower the reel the operator may grasp the hand-lever d on the rock-shaft a', and by either giving it a backward or forward movement causes the 75 segments a² on each end thereof to raise or lower the reel-frame by the same rocking upon the pivot in the forked standards b b², and when adjusted the reel and reel-frame is held in position by the spring-pawl d' engaging the teeth 80 of the semicircular plate d², secured to the inner standard, A'. In shifting the reel backward or forward the hand-lever a⁷ may be thrown in either direction back or forth, which has the effect of operating the sliding bars b⁵ 85 b⁵ simultaneously, and when in the desired position the spring-pawl d³ engages the teeth of the plate d⁴, thereby securing the hand-lever a⁷ and reel in place.

It will be seen that the reel may be adjusted 90 in four different positions—viz., an upward, downward, forward, and backward—and when so adjusted can be held in place by the levers a⁷ and d. At the same time the belt-tightener c⁶ keeps the belt always taut for operating the 95 reel.

What I claim, and desire to secure by Letters Patent, is—

1. In a harvester, the combination of the reel-bars a⁴ a⁴, having the loops b⁴, sliding bars 100 b⁵, carrying the reel-shaft b⁷, having bearings b⁶, connected by the links c⁴ to the lever a⁷, the

rock-shaft a^5 , having bent arm a^6 , the shaft a' , having segments a^2 , and hand-lever d of the belt-tightener c^6 , constructed as set forth, for the purposes described.

5 2. In a harvester, the reel-frame consisting of the side bars, a^4 , pivoted to the standards b^2 , the sliding bars $b^5 b^6$, rock-shaft a^5 , having the bent arm a^6 , and lever a^7 , connecting-links c^4 , and the segments $a^3 a^3$, secured to the rear 10 end of the side bars, $a^4 a^4$, operated upon and

in combination with segments $a^2 a^2$ on the rock-shaft a' , having hand-lever d , spring-pawl d' , and the slotted standard b' , as shown and described.

In testimony whereof I affix my signature in 15 presence of two witnesses.

KITTEL ANUNSEN.
